RACK

William B. Hay, Portland, Maine

Application December 15, 1933, Serial No. 702,591

3 Claims. (Cl. 211—41)

This invention relates to kitchen accessories in the nature of racks for storing and holding pans, plates, and pot covers. An object of the invention is the provision of an improved metal 5 wire rack of openwork construction arranged to receive a plurality of different sized relatively flat articles such as pie plates, shallow pans, and pot covers, in readily accessible and nested relation. Another object is the provision of a rack 10 of this nature that is equally adapted for table or wall support, and that supports contained articles on edge. Other objects will be apparent from the description.

The present disclosure deals with a preferred 15 form of the invention. It is to be understood that the structural details thereof may be varied as desired in any embodiments not inconsistent with the scope of the invention as claimed. In the drawing:

20 Figure 1 is a perspective view of the rack.

Figure 2 is an elevation of the rack illustrating the disposition of contained articles.

Figure 3 is a reduced top plan view of the rack.

The rack is made up of a plurality of wire 25 frames assembled in basket form by rigid connection between the frames at their points of contact. Metal bars or strips may be used in lieu of wire if desired.

In the illustrated embodiment the rack 30 comprises a horizontally disposed rectangular wall frame W, a base frame B, and a pair of partition frames P disposed in the assembled relation shown in Figure 1 and rigidly united by suitable means, such as solder or spot welds at all points 35 of contact. All frames are of one-piece construction.

The base frame B consists of a pair of parallel 40 bottom bars 5 upturned in right angles at their ends to form pairs of uprights 6 connected by top bars 7, the length of the top bars determining the spacing of the parallel bars 5 and 6. The horizontal wall frame W is disposed within the base frame and consists of end bars 8 and parallel side bars 9, the bars 9 being attached to the 45 uprights 6 at approximately one third their height above the bottom bars 5.

Each partition frame P has its entire length 50 disposed in a single vertical plane, and these frames are disposed longitudinally of the rack, 55 being with the upright sides 6, in mutually spaced parallel relation. Each partition frame consists of a bottom bar 10 attached to and overlying the bars 5 and upturned at each end to provide end wall bars 11 attached to and overlying the wall frame end bars 8. Just above the wall frame

the bars 11 are inclined inwardly and upwardly as diagonal bars 12, being connected by horizontal top bars 13 disposed substantially in a horizontal plane common to the top bars 7 of the uprights 6. The partition top bars 13 are substantially coextensive in length with the top bars 7.

It will be readily apparent that a greater or lesser number of the partition frames may be employed, as desired, and that these frames may 10 be made entirely rectangular instead of in the form shown, without departing from the principles of the invention.

This rack is peculiarly adapted to the 15 convenient storage of relatively flat articles of circular shape, such as covers, pie pans, and the like. In Figure 2 is shown the disposition of a pot cover 14 and a pie pan 15 supported on edge. In this manner a large number of such articles 20 may be stored simply by nesting between the partition frames and the upright side frames at front and rear.

The contained articles lean upon the partition and side frames, the bottom bars 10 serving as 25 abutments against which the edges of the articles rest, thus preventing too great an inclination and thereby increasing the capacity of the rack and the accessibility of contained articles.

The length and spacing of the bottom bars is 30 such that the rack cannot tilt when supported on a flat surface, such as a table top or shelf. When wall supported, the vertical disposition and spacing of the uprights 6 insures the maintenance 35 of the rack in a horizontal position so that its contents cannot be spilled.

I claim:

1. A rack comprising a rectangular wire frame having a much greater length than width and being bent in right angles toward its ends to provide parallel spaced uprights, a rectangular wire frame disposed horizontally between said uprights and contacting the same, and a substantially rectangular wire frame disposed in a vertical plane between said uprights and parallel thereto, said vertical frame contacting the horizontal frame at the ends thereof and contacting the bars of said first named frame inwardly of the rack to form with said bars the bottom of the rack.

2. A rack for supporting substantially flat circular articles on edge, comprising an open-work wire basket-like body having a one-piece wire frame shaped to provide parallel upright side pieces integrally united by a single pair of spaced parallel bars forming the rack bottom, a sub- 55

stantially rectangular wire frame disposed horizontally between said side pieces to provide side and end walls for the rack, and partition means seated on said pair of parallel bars at right angles thereto to provide rack bottom abutments for the edges of articles when leaning in the rack against said side pieces.

3. A rack for supporting substantially flat circular articles on edge, comprising an open-work body consisting of two end bars and two side bars disposed in a common horizontal plane, an upright at each side of the rack at the middle por-

tion of said side bars and extending thereabove to provide rests against which articles may lean, a single pair of parallel bars connecting said uprights to provide the rack bottom, and at least one partition frame parallel to said side bars and connected to said end bars and having a bottom bar seated inwardly upon said pair of bottom bars at right angles thereto, the interior of the rack being unobstructed longitudinally between said partition frame and the side bars.
